UNITED STATES PATENT OFFICE.

KARL H. CEDERLUND, OF DUQUESNE, PENNSYLVANIA.

MULE.

1,117,636.

Specification of Letters Patent.

Patented Nov. 17, 1914.

Application filed August 29, 1914. Serial No. 859,142.

To all whom it may concern:

Be it known that I, KARL H. CEDERLUND, a citizen of the United States, and resident of Duquesne, in the county of Allegheny and State of Pennsylvania, have invented certain new and useful Improvements in Mules, of which the following is a specification.

My invention relates to car hauls used with car dumping mechanism and similar apparatus, employing a pushing car or mule for transferring loaded cars to the platform of a car dumping mechanism, and more particularly relates to the construction of the pushing car or mule forming part of the car haul and the means employed in bringing the mule into position for loaded cars to be engaged by the pushing arm.

One object of my invention is to provide a car haul having a pushing car or mule of improved construction and having novel means enabling the mule to pass under railroad cars positioned on the track of the car haul in moving the mule into car hauling position.

Another object of my invention is to provide a car haul mule of improved construction and having novel means for lowering the pushing arm of the mule.

A further object of my invention is to provide a mule having a lifting pushing arm and having novel means for raising the lifting arm and holding the arm in raised position.

A still further object of the invention is to provide a mule having improved means for disengaging the arm holding mechanism, and for lowering the raised lifting arm of the mule.

Still further objects of my invention will be disclosed as the invention is more fully described hereinafter and is specifically pointed out in the appended claims.

Referring now to the drawings forming part of this specification, Figure 1 is a vertical sectional side elevation of a car haul having a mule and mule actuating mechanism constructed and arranged in accordance with my invention. Fig. 2 is a plan of the apparatus shown in Fig. 1. Fig. 3 is a detail plan, on a larger scale, showing the construction and arrangement of the switches by which the pushing arm of the mule is disengaged and lowered from its lifted or car pushing position. Fig. 4 is a

sectional plan, on a larger scale, shewing in detail the mule as constructed in accordance with my invention. Fig. 5 is a sectional side elevation of the mule shown in Fig. 4, the section being taken on the line V—V of Fig. 4. Fig. 6 is an end elevation of the construction shown in Figs. 4 and 5. Fig. 7 is a sectional end elevation of the apparatus of Figs. 4, 5 and 6, the section being taken on the line VII—VII of Fig. 5.

In the accompanying drawings, the numeral 2 designates the rails of the inclined track of a car haul upon which railroad cars 3, to be emptied of their load, are transferred to the platform of a car dumping mechanism by means of the mule forming my invention, such car dumping mechanism being an appliance used in unloading cars by inverting the loaded cars to discharge their contents in bulk into a conveniently located chute or hopper. Extending parallel with the track rails 2, in a depression or pit 4 between these rails, are rails 5, 5, of a depressed track upon which the mule or pushing car 6 is mounted. Positioned between the rails 5, 5, of the depressed pushing car track at the bottom, and adjacent to the top of the inclined portions of the car and mule tracks, are arm lifting rails 7 and 8 which are provided for a purpose described hereinafter. Also located adjacent to the top of the inclined portions of the tracks, on opposite sides of the lifting rail 8 are switch rails 9 and 10 (see Figs. 3, 6 and 7). These switch rails extend lengthwise at an angle to the lengthwise center of the track rails and are pivotally secured at one end to the ties of the depressed track in the pit 4.

Mounted in the pit 4 to travel on the track rails 5, 5, of the depressed track is the mule or pusher car 6, the mule having track wheels 11 on axles 12 which are in bearings 13 on the main frame 6 of the mule. Pivotally mounted at its rear end by a pin 14, to lugs 15 formed integral on the frame of the mule 6 is a swinging or lifting pusher arm 16. The free or swinging end of the arm 16 is provided with marginal flanges 17—17 and a curved surface 18 which engage with the coupler of a standard railroad car in operating the mule to transfer a loaded railroad car on the track rails 2, 2 of the car haul.

Pivotally secured by a pin 19 to the pushing arm 16 at an intermediate point in the

length of arm is an eyebolt 20, a helical spring 21 on the eye-bolt affording means for cushioning the pulling action of the hauling cable 22, one end of which is secured 5 to the eye-bolt. The other end of the cable is connected to a winding drum (not shown) or other hauling device to actuate the mule on the depressed track and this mechanism being old and well-known and not forming 10 part of this invention is not further described.

Pivoted on a pin 23 between the ends of the integral lugs 24 which extend downwardly from the sides of the pushing 15 bar is an anti-friction roller 25 which engages with the lifting rails 7 and 8 that are located between the rails 5, 5 at the bottom, and adjacent to the top respectively of the inclined portion of the depressed track in 20 the pit 4. The pushing arm 16 has lugs 26 on the outer surfaces of the vertical sides of the arm, arranged to be engaged by the upper ends of the swinging levers 27 which are pivoted by pins 28 on the pairs of lugs 29 25 extending inwardly from the inner surfaces of each side of the car frame 6. The lower ends of these levers 27 extend downwardly below the plane of the top of the track rails 5 and helical springs 30 connected to the levers 30 and to the sides of the mule frame 6 are employed to move and yieldingly hold the levers in engaging position relative to the lugs 26 on the pushing bar 16 or the position shown in Figs. 4, 5 and 7. The depending 35 ends of the levers 27 are arranged to engage with the switch rails 9 and 10 at the top of the inclined portion of the depressed track when the pushing arm 16 is being lowered. When engaged in the pusher arm lowering 40 operation by the switch rails 9 and 10 the levers 27 are moved inwardly so as to swing the upper ends thereof out of engagement with the lugs 26 on the sides of the pushing arm 16. This permits the pushing arm to be lowered until its forward end rests on the 45 end of the main frame 6 of the mule or in the position shown by broken lines in Fig. 5.

To prevent the pusher arm falling and possibly breaking or causing damage to itself 50 or other parts of the pusher car, the lifting rail 8 is positioned between the switch rails, and the lifting rail 8 being inclined on its ends as is shown in Fig. 1, the pusher arm is gently lowered from its raised position into 55 its lowered position. When the car reaches the lower end of the inclined portion of the tracks the anti-friction roller 25 on the pushing arm engages with the lifting rail 7 between the tracks at the bottom inclined portion 60 of the track and by engagement with this lifting rail its outer swinging end is lifted until again in the position shown in Fig. 5. As it reaches this position the springs 30 on the lower ends of the levers 65 27 move the upper ends of the levers in-

wardly so as to engage the lugs 26 on the sides of the pushing bar and securely hold the pushing arm 16 in its raised position until it is again disengaged at the top of the inclined portion of the depressed track. 70 When the pushing car is moving upwardly on the inclined track to shift a loaded car 3 to the platform of a car dumper, the lower ends of the pivoted levers 27 on the car frame engage with the outer surfaces of the 75 switch rails 9 and 10 and move these rails inwardly against the resistance of the springs 31. When the mule has moved upwardly on the track a distance sufficient for the depending ends of the lever arms 27 to 80 clear the upper ends of the switch rails 9 and 10, the springs 31 act to spread or draw the switch rails outwardly until again in the position shown in Figs. 2 and 3.

In the operation of my improved apparatus the mule will be actuated by a suitable winding mechanism having a hauling cable, one end of which is attached to the eye-bolt 20 on the pushing arm of the pushing car. A loaded car 3 is moved by a locomotive on 85 the rails 2, 2, forming the track into the position shown in Fig. 1. As the mule reaches this position the anti-friction roller 25 on the pushing arm engages with the lifting rail 7 between the track rails of the depressed track and lifts the pushing arm 16 into the position shown in full lines in Fig. 5. When lifted into this position the springs 30 attached to the lower ends of the levers 27 which are pivoted to the sides of the mule 90 act to move the upper ends of these levers into engagement with the lugs or stops 26 on the sides of the pushing arm 16. The winding mechanism is then actuated to move the pushing arm until its forward end engages with the coupler or draw head of the loaded freight car 3 to travel upwardly on the inclined track until it is delivered on the platform of a car dump or other position desired on the track at the top of the inclined 95 track. In the meantime, another loaded car is positioned, as shown in Fig. 1, by a locomotive. The mule is then caused to travel downwardly on the inclined track. At the beginning of its downward movement the 100 lower ends of the pivoted levers 27 engage with the inner surfaces of the pivoted switch rails 9 and 10 located between the rails 5, 5 of the depressed track, as shown in Fig. 7. Engagement of the lower ends of these pivoted levers moves their upper ends outwardly until clear of the lugs 26 on the sides 105 of the pushing arm 16, the anti-friction roller 25 on the pushing arm being engaged by the lifting rail 8 located between the 110 switch rails 9 and 10. The upper or swinging end of the pushing bar is thereby lowered by the inclined portion of the lifting rail 8 until it rests on the end of the main 115 frame of the mule in the position shown by 120

125 130 135

broken lines in Fig. 5. As the mule passes beneath the next loaded car and reaches the position shown by full lines in Fig. 1, the pushing arm 16, after being raised is again raised and is held in lifted position by the levers 27 in the manner which has been described. The above described operations are then repeated with successive cars in moving the loaded cars upwardly on the inclined track.

The advantages of my invention will be apparent to those skilled in the art. By the use of my improved apparatus the pushing arm of the mule is mechanically moved into and out of its raised position and is positively held in raised position while shifting loaded cars on the inclined track.

The apparatus is simple and is easily kept in repair. By its use the necessity of positioning the mule in a pit before loaded cars can be moved into position to be transferred on the inclined track by the mule is avoided and overcome.

Modifications in the construction and arrangement of the parts may be made without departing from my invention as defined in the appended claims.

I claim:

1. In a car haul, a mule comprising a wheeled car frame, a pushing arm pivotally mounted on said frame, means connecting said mule with a haulage rope, means for raising said arm at predetermined points in the length of the car haul track, means on said frame for holding the arm in raised position, and means between the track rails of the car haul track for disengaging the arm holding means.
2. In a car haul, a mule comprising a wheeled car frame, a pushing arm pivotally mounted on said frame, means connecting said mule with a haulage rope, means for raising said arm at predetermined points in the length of the car haul track, means on said frame for holding the pivoted arm in raised position, means between the track rails of the car haul track for disengaging the arm holding means, and means between the rails of the car haul track for lifting said pivoted arm.
3. In a car haul, a mule comprising a frame movable along the track of the car haul, a pushing arm pivoted to said frame, means on the car haul track for lifting the pivoted arm, means on said arm engaged by the arm lifting means to raise the swinging end of said pushing arm, and means on said

frame for holding the pushing arm in lifted position.

4. In a car haul, a mule comprising a frame movable along the track of the car haul, a pushing arm pivoted to said frame, means on the car haul track for lifting the pivoted arm, means on said arm engaged by the arm lifting means to raise the swinging end of said pushing arm, means on said frame for holding the pushing arm in lifted position, and means on the car haul track for disengaging the arm lifting means to lower the arm on said frame.

5. In a car haul, a mule comprising a frame movable along the track of the car haul, a pushing arm pivoted to said frame, means on the car haul track for lifting the pivoted arm, means on said arm engaged by the arm lifting means to raise the swinging end of said pushing arm, means on said frame for holding the pushing arm in lifted position and means for disengaging the arm holding means and lowering the arm on said frame.

6. In a car haul, a mule comprising a wheeled frame, a pushing arm pivotally mounted on said frame, means pivoted on said arm for connecting a haulage rope to said mule, depending lugs on the pushing arm, an anti-friction roller between said lugs, means between the car haul track rails engaging said roller to raise and lower said arm at predetermined points in the length of the car haul track, and means on the mule frame for holding the pushing arm in raised position.

7. In a car haul, a mule comprising a wheeled frame, a pushing arm pivotally mounted on said frame, means pivoted on said arm for connecting a haulage rope to said mule, depending lugs on the pushing arm, an anti-friction roller between said lugs, means between the car haul track rails engaging said roller to raise and lower said arm at predetermined points in the length of the car haul track, means on the mule frame for holding the pushing arm in raised position, and means on the car haul track for disengaging said arm holding means in lowering the lifted pushing arm.

In testimony whereof, I have hereunto set my hand.

KARL H. CEDERLUND.
